JULES VERDOL, OF LYONS, FRANCE.

JACQUARD MECHANISM FOR LOOMS.

SPECIFICATION forming part of Letters Patent No. 729,706, dated June 2, 1903.

Application filed January 20, 1903. Serial No. 139,838. (No model.)

To all whom it may concern:

Be it known that I, JULES VERDOL, a citizen of France, residing at Lyons, Rhône, France, have invented certain new and useful Improvements in Jacquard Mechanism for Looms, of which the following is a full, clear, and exact description.

The improvements forming the subject of the present application have for their object to enable jacquard mechanism, and particularly such mechanism employing continuous perforated paper, such as described in Letters Patent No. 346,877, granted to me August 3, 1886, to work at an increase of speed of sufficient amount to enable them without inconvenience to work at the maximum speed of the looms for weaving to which they are applied. At present jacquard mechanism can only endure a moderate speed, which is much less than that which the loom could attain. This would result in an abrupt engagement of the ratchet mechanism, which causes the cylinder and paper to advance, and would communicate to these latter confusions which would prevent all precision beyond a certain speed and would rapidly deteriorate the paper and the parts carrying and operating it. According to the present invention this inconvenience is suppressed by a particular arrangement of friction-pawl gearing with progressive engagement, thus suppressing shocks and insuring the stoppage of the paper at its exact position. This arrangement is represented by the accompanying drawing, which is an end elevation showing the invention applied to jacquard mechanism of Verdol's system.

The cylinder *a*, suspended below the vertical needles of the jacquard by pivoted levers *b*, carries, as usual, a lantern-wheel *c*, which no longer serves to cause the cylinder to advance, but only to fix it in correct position by the holdfast-pulley *d* and to effect by hand the backward motion by means of the pawl *f*. The forward movement of the cylinder is effected by a friction-pawl *e*, jointed to an arm *h*, oscillating on the axle of the cylinder. The pawl *e*, furnished or lined with india-rubber or other adherent material *e'*, is applied to the circumference of a disk *g*, fixed to the cylinder. The hook *j*, which in former arrangements caused the cylinder

to advance by acting on the lantern-wheel *c*, acts, according to the present invention, on the tail of the pawl *e*. It is put in motion, as usual, by the forward motion of the lever *l*, and in rising vertically it produces the double effect of applying the pawl *e* to the circumference of the disk *g* and of causing it to advance in the direction of the arrow. At the same time the holdfast-pulley *d* is pushed back by a cam *i*, fixed rigidly to the arm *h*, carrying the pawl, thus enabling the cylinder to rotate without shock. When the lever *l* arrives near its extreme forward position, a pusher *m*, which is fixed to it, pushes the hook *j*, which abandons the tail of the pawl *e*. This latter then ceases to press on the disk *g* and returns to the rear, being drawn by the spring *k*. The holdfast-pulley *d*, abandoned by the cam *i*, returns into engagement between two pins of the lantern-wheel *c*, thus bringing the cylinder to and fixing it in its exact position. The cylinder can then accomplish its function upon the needles, and when it again descends it replaces the tail of the pawl *e* in gear with the hook *j* to the position shown in the drawing. By this arrangement the paper is drawn forward without shocks, the cylinder, being always held, cannot by its inertia pass beyond the point where it should stop, and the inconveniences due to great speed are suppressed.

What I claim as my invention, and desire to secure by Letters Patent, is—

1. In combination in jacquard mechanism, a cylinder, a disk *g* thereon, a friction-pawl *e* pressed against the said disk *g*, a hook *j* for pushing the pawl forward, a holdfast-pulley *d* arranged to fix the position of the cylinder, and means connected to the said pawl whereby the holdfast-pulley will be pushed forward on the movement of the said pawl, substantially as described.

2. In jacquard mechanism, and especially those which utilize continuous perforated paper, the combination of a cylinder suspended below the vertical needles, pivoted levers supporting said cylinder, a lantern-wheel fixed to said cylinder, a holdfast-pulley acting against such lantern-wheel to secure the cylinder in correct position, a cam acting on said holdfast-pulley, a pawl operated by hand to act on the pins of said lantern-wheel

to give a backward motion thereto, a friction-pawl to give forward motion to the cylinder, an arm oscillating on the axis of the cylinder to which such friction-pawl is pivoted and to
5 which the cam is rigidly fixed, a lining of adherent material to said friction-pawl, a disk fixed to the cylinder against which such friction-pawl operates, a hook acting on the tail of the friction-pawl to cause the latter to act

on the disk, a spring to move said friction-pawl backward, and a lever giving motion to said hook, substantially as herein set forth.

In witness whereof I have hereunto set my hand in presence of two witnesses.

JULES VERDOL.
